ABSTRACT OF THE DISCLOSURE

Method and apparatus for making envelopes from a moving strip of paper unwinding from a roll. The moving strip cut into individual strips having alternate wide and narrow portions, adjacent strips relatively displaced to bring wide portions opposite for subsequent gluing, folding, cutting, and subsequent operations.

This invention relates to a method and apparatus for making envelopes from an elongated strip of foldable material when the strip is moving in the direction of its length.

In the manufacture of envelopes it is customary to either cut envelope sections from a sheet of material and to then fold and glue the sections into envelopes or, in some cases, to cut the sections from a single strip of material and then move the cut sections to a mechanism that will glue and fold the sections into envelopes.

This procedure is extremely costly both as to the wastage of material and labour and I have found that a considerable percentage of the cost of envelopes can be attributed to this high wastage of material and labour.

Roughly speaking, there are about 300 million envelopes used daily in the United States of America and it is obvious that if a saving of even ten or fifteen percent in materials could be made there would be a considerable saving in the ultimate cost of the envelopes to the purchaser.

The multipath method of making bags from an elongated strip of foldable material moving in the direction of its length is well known and in this method it is common to cut the strip of material longitudinally into a plurality of strips with side flaps that are then folded onto the strip. Adhesive is then applied to the folded flaps and the strip is cut into convenient sections that are folded to form a bag open at one end.

In essence, my invention utilizes a multipath machine of the type for making bags wherein the strip of foldable material is cut longitudinally as in the manufacture of bags and the side flaps are folded onto the strip so that adhesive may be applied as required. In my invention the cutting of the strip into envelope sections differs from the conventional bag cutting in that the strip is cut so that an envelope flap will be formed at the leading edge of the envelope section. After the section is folded to form an envelope closed at the sides and bottom, the flap projects in the same manner as a conventional envelope flap and I then provide means whereby the flap may be folded back onto the envelope to act as an envelope closure. If desired, I provide means whereby the trailing edge of the envelope section may be notched to provide a finger cut out and wherein the envelope flap may be cut into a V-shape to provide a flap similar to conventional envelope flaps.

In drawings illustrating my device:

FIGURE 1 is a plan view of an envelope section prior to folding and with the finger cut out and envelope flap cut off portions shaded.

FIGURE 2 is a view similar to FIGURE 1 with the side flaps folded.

2

FIGURE 3 is a view of the envelope section with the back of the envelope folded onto the side flaps.

FIGURE 4 is a view of the completely folded envelope.

FIGURE 5 is a plan view of a strip of material showing 5 the longitudinal cutting lines.

FIGURE 6 is a top plan view showing four strips of material in linear alignment and with the side flaps folded.

FIGURE 7 is a diagrammatic side elevation showing 10 a machine modified to produce envelopes.

With reference now to the drawings, as seen in FIGURE 1, an envelope in its completely unfolded condition consists of a substantially rectangular sheet of foldable material, as for example, paper formed to include a central portion comprising the front 1 and back 2 of an envelope. A pair of flap portions 3 are formed at the sides of the envelope and these are folded onto the central portion of the envelope as indicated in FIGURE 2 in the drawings. A suitable glue or other adhesive 3a is then applied to the exposed faces of the flap portions 3, the back portion 2 then is folded along the transverse fold line 5 to produce an envelope of the form shown in FIGURE 3 in the drawings.

With reference now to FIGURE 7 in the drawings I 25 will describe a machine modified to produce envelopes.

This machine consists of a supporting apparatus indicated generally at 8 with a supply roll of flexible material 9 mounted rotatably at one end of the support. A strip 10 of flexible material whose width is represented as W in 30 FIGURE 5 in the drawings, is passed over a guide roller 11 to cutting wheels 12 and 13 which cut the strip 10 into a plurality of individual strips 35, 36, 37 and 38 as represented in FIGURE 5 in the drawings. Each of the strips is composed of alternate narrow and wide portions 35, 47 and 45 which are displaced relative to each other to minimize any waste material between adjacent strips. The only waste will occur at the shaded portions 39 and 46 35 at the outer edges of the strips 35 and 38. This waste is sucked off through the suction mechanism 13a in conventional fashion.

The separated strips are then passed to the folding means 14 which folds the flaps 3 as indicated in FIGURES 2 and 6 in the drawings. To bring the strips into linear alignment with each other, either the strips 35 and 45 or 36 and 38 are passed to an auxiliary roller 15 so that the strips would be linearly displaced by the time they reach the roller 11b, since the path from an auxiliary roll 11a directly to 11b is shorter than via the auxiliary roll 15.

The strips are then passed to the draw rollers 17 and a suitable glue applicator 16 where glue 3a is applied to the folded flaps 3, and to an inner surface of the flap 4 adjacent its outer edge. It is clear that, for gluing to be accomplished in the manner indicated, the wide and narrow portions, as cut, are uniformly spaced.

The foregoing apparatus is well known in the art and at this point the strips could be cut to provide bag sections which would be folded into a simple bag open at one end.

To construct envelopes, the strips are now moved to the separator device 18 where they are cut along the lines 40 as seen in FIGURE 6 in the drawings. It will be seen that the cutting of the strips into the sections at the lines 40 whose length is represented by "l" will provide envelope sections with an envelope closure flap 4 at the leading edge of each section and with the back portion 2 of the envelopes at the trailing end of each section.

Each individual section is then folded along its transverse fold line 5 (FIGURE 6) by means of a conventional folding tool 19 which is carried by the rotating tool carrier 20. The tool 19 is received within slot 51 in a first rotatable folding cylinder 25 so that each section is

gripped at the fold line 5 in the slot 51 and is folded transversely as it passes beneath a plate 21.

If desired, finger cut outs 43 may be made in the sections by a rotating tool 24 which extend into slots in the folding cylinder 25 and which cut out the shaded sections 43 to provide the finger cut outs in the back 2 of each section. The finger cut out is thus made substantially simultaneously with the transverse folding above.

It will thus be seen that, at the cylinder 25, the sections will be folded at the line 5 with the back 2 of each envelope glued on the flaps 3 and with finger cut outs 43 cut at the trailing edges if desired.

While each folded envelope is held at the fold line 5 in the slot 51, a second rotating cutting knife 22 co-operating with a slot 26 in the cylinder 25 cuts out the shaded portions 42 of the flaps 4.

The folded envelopes now are transferred from the first folding cylinder 25 to a second folding cylinder 30 by a folding tool 27 which engages with the envelopes at the line 44 and folds the flaps 4 of the envelopes so that the folds will be gripped in a slot 29 of the second folding cylinder. At this instant the slot 51 will open to release the bottoms of the envelopes at the fold line 5 and the envelopes can then be transferred to a discharge cylinder 31 to be picked up by grippers 32 and deposited in stacks 33 on a rack 34.

While not illustrated, it will be obvious that meshing gears would be secured on the shafts of the folding cylinders 25 and 30 and the discharge cylinder 31 so that the cylinders would be rotated at the correct speeds and there would be conventional mechanism to release the envelopes as they were transferred from one cylinder to the other.

The embodiments of the invention in which an exclusive property or privilege is claimed are defined as follows:

1. In a method of making envelopes from a strip of foldable material moving in the direction of its length, the steps of:

- (a) effecting a longitudinal cut in the moving strip dividing it into two adjacent individual strips,
- (i) the individual strips having alternate uniformly spaced wide and narrow portions,
- (ii) the wide portions being adapted to be folded to form side flaps of the envelope;
- (b) folding the wide portions on lines defining side edges of the envelopes to form the side flaps;
- (c) causing motion of one individual strip relative to the adjacent individual strip as to align the folded flaps to be opposite one another;
- (d) cutting the individual strips along transverse cut lines intermediate the aligned flaps, dividing the individual strips into envelope sections,
- (i) having a generally rectangular back portion, an outer edge of which is defined by a transverse cut line aforesaid,
- (ii) a front portion between the folded flaps,
- (iii) and a generally rectangular closure flap, an outer edge of which is defined by a transverse cut line aforesaid;
- (e) applying an adhesive to exposed side flap faces, and to an inner surface of the closure flap adjacent the outer edge thereof;
- (f) folding each envelope section transversely on a

line joining ends of the folded flaps adjacent the back aforesaid, and placing the back in contact with the glued side flap surfaces.

5 2. A method as set forth in claim 1, wherein; the envelope sections are further cut so that the closure flaps are generally triangular having apices which, before folding, extend outwards of the front portion.

10 3. A method as set forth in claim 2 wherein; the envelope sections are further cut to provide finger cut outs of the back portion, the further cutting being effected substantially simultaneously with the transverse folding aforesaid.

15 4. In an apparatus for making envelopes from a strip of foldable material moving in the direction of its length, the combination of:

15 (a) means continuously to divide the moving strip into two adjacent individual moving strips,

20 (i) the individual strips being divided to have alternate uniformly spaced wide and narrow portions,

25 (ii) the wide portions being adapted to form side flaps;

(b) a first folding means constructed and arranged to fold the wide portions on lines defining side edges of the envelopes, to form side flaps;

30 (c) means to cause motion of one individual strip relative to the adjacent individual strip thus aligning the folded side flaps;

(d) means to cut the individual strips along transverse cut lines intermediate the aligned side flaps,

35 (i) having a generally rectangular back portion, an outer edge of which is defined by a cut line aforesaid,

40 (ii) a front portion between the folded flaps,

45 (iii) and a generally rectangular closure flap, an outer edge of which is defined by a transverse cut line aforesaid;

(e) means to apply an adhesive to exposed faces of the side flaps, and to an inner surface of a closure flap adjacent the outer edge thereof;

40 (f) a second folding means adapted to fold each envelope section transversely on a line joining ends of the folded side flaps adjacent the back portion, placing side edges of the back in contact with the glued side flap surfaces.

5 5. A combination as set forth in claim 4; and means to cut a closure flap to generally triangular shape having an apex which, before folding, extends outward of the front portion.

6. A combination as set forth in claim 5, the second folding means having a further cutting means adapted to provide a finger cut out of the back portion substantially simultaneously with the transverse folding.
